UNITED STATES PATENT OFFICE.

LUDWIG WALLSTROM, OF LIMA, PERU.

BURNER.

Application filed November 17, 1926. Serial No. 148,917.

My present invention relates to burners, and has for its principal purpose to improve burners of the kind disclosed in my United States Letters Patent No. 1,588,634, dated 5 June 15, 1926, although it will be plain that features of my present invention are applicable to various other burners adapted to use liquid, gaseous or powdered fuel.

In particular, I desire to provide for controlling the flow of air between the nozzle and the cooperating, reversible ring mounted therein. Another purpose is to improve the mechanism whereby the nested fuel tubes are cleaned when firing is stopped. Another 10 purpose is to provide such a valve stem or other member extending through the inner fuel tube as will cause the air, fuel or both passing through said tube to issue therefrom with a whirling motion. Another purpose 15 is to provide improved means for supplying and straining the oil, and a still further purpose is to mount the burner rotatably, whereby the flame may be played in any desired direction. Another purpose is to provide a 20 better adapted and improved mechanism for shifting the nested tubes. Still another purpose is to provide an air connection between the air supply pipe and the rear end of the fuel tubes. 25 The invention resides in the elements, features and combinations claimed in the appended claims, and now, in order, that the invention may be fully understood and readily put into practice, the same will be described with reference to the preferred embodiments shown in the accompanying drawings which, it is to be understood, are only 30 for the purpose of illustration, so that my invention includes all changes and modifications as fall within the scope of said claims.

In said drawings:

Figure 1 is a view, partly in vertical longitudinal section and partly in side elevation, of the improved burner constructed in accordance with my present invention.

Fig. 1^a is a side elevation of a cap nut adapted to close the rear end of the inner fuel tube when the burner is operated without a valve at the nozzle end of said tube.

Figure 2 is a sectional view of an oil filter and connections for supplying oil to the fuel-conveying tubes of the burner.

Figure 3 is a transverse section through the burner, showing in elevation certain air valves for the nozzle.

Figure 4 is a fragmentary sectional view

of the forward part of the nozzle and the fuel-conveying tubes, showing a modified form of valve stem.

Figure 5 is a fragmentary sectional view 60 of the forward part of the nozzle and the fuel-conveying tubes, showing a modification in which there is no valve cooperating with the inner fuel tube, said tube containing a helically twisted element, adapted to 65 cause the gases or powdered fuels conveyed by the flow of air through said tube to take a tortuous or helical course.

As in my aforesaid patent, the burner in the present instance comprises an elbow 1, 70 into which is threaded a sleeve 2, appropriately connected with a nozzle 3. An air conduit 5, preferably stationary, leads to the lower opening in the elbow 1, and the burner is supported on this air conduit. Air 75 may be supplied through said conduit, at any desired pressure, by a fan, blower or other source.

Two telescoping or nested tubes 6 and 7 extend centrally through the nozzle and 80 through the horizontal turn of the elbow, passing through the rear vertical wall thereof. The space between the outer tube 6 and the inner tube 7 constitutes a fuel passageway, and the space within the inner tube 85 also constitutes a passageway 4 for fuel as well as for air. A rod or stem 8, within the inner tube, has a valve 9 at its forward end, and a deflector plate 10, having a partly spherical rear surface, is secured to the end 90 of tube 7, said plate providing a valve seat 11 to cooperate with valve 9, and a valve seat 12 to cooperate with a replaceable sleeve 13 secured to tube 6. A ring 14 having a conical inner surface 15 surrounds the atomizer or plate 10, and is held slightly spaced from the inner wall of the nozzle 3 by pins 16 preferably three in number.

An interiorly threaded bushing 17 secured in the wall of the sleeve 2 receives pipe sections 18 and 19, and the latter supports a four-way joint 20 through which extend the tubes 6 and 7. These tubes and the valve stem 8 are permitted to slide but held against rotation with respect to the joint 100 20 by means of a pin (not shown) extending from the joint 20 into a slot formed in the side of the tube 6. The tube 6 also has two slots 22 more to facilitate the commingling of fuel or air, and for cleaning purposes. The two tubes with the valve stem and atomizing plate 10 are adapted to be axially 105 110

shifted through the joint 20 a distance substantially equal to the axial length of the ring 14, by means of an eccentric portion 57 receiving an anti-friction ring 58, and the latter is held in place by a lower shoulder 57^a and fits between the two shoulders of sleeve 64, said sleeve being threaded and secured on the outer tube 6. The eccentric portion is mounted for movement on an angle bracket 53 bolted to the elbow 1; said bracket has a semicircular arcuate flange 54, and a bearing 69, to engage the vertical cam shaft 57^b, whose upper end is enlarged and has a key or feather 67, to fit slidably in a slot formed in the hollow vertical shaft 56. A spring 55 is secured on the top of shaft 56 by the screws 63. Said spring slides underneath the arcuate flange 54, provided with grooves, and numerals may be inscribed on the radial face, divided in five portions from 0 to 5, to indicate the adjusted position occupied by the plate 10 in the ring 14. The vertical shaft provided with a hand-wheel 56^a is adapted to be rotated through an arc of 180°. Locking nuts 61 and 62, the latter if desired having a cotter pin or the like, are threaded on the shaft 57^b to hold shaft 56 and wheel 56^a in place, and may be tightened to lock the cam 57 against the bearing 69, so as to hold the tubes in any desired position of adjustment.

The inner tube 7 is adjusted with respect to the outer tube (to a very limited size of an oil outlet opening between valve 12 and seat 13) by means of a handle 39 threaded in the rear end of sleeve 64, and adapted to advance or retract tube 7 to the desired extent. The valve stem 8 is adjusted within the inner tube 7 (to vary the clearance between valve 9 and its seat 11) by means of a hand wheel 45 threaded in the joint 42, and adapted to advance or retract stem 8 to the desired extent. As actually shown, the burner is adapted to produce a spherical, broad, enlarged long flame, and should the burner be required to produce a narrow, elongated flame, it is merely necessary to reverse ring 14 and to eliminate valve 9, stem 8, and hand-wheel 45, and provide in lieu of said wheel on the joint 42, the cap-nut 68. The latter closes the opening in the rear of joint 42, and the burner arranged in that condition, adjusted as above said, is set for a narrow, elongated flame. The atomizer or deflector plate 10 is provided in three different sizes for use in one and the same burner to project flames of different form, size and length. Fig. 4 shows a plate 10 and nozzle 3 smaller than those of Fig. 1, and Fig. 5 shows a still smaller plate 10, with a nozzle of the same size shown in Fig. 4. The smaller ring 14 and plate 10 of Fig. 5 may be used by providing a fixed ring 53 secured in said nozzle.

65 The parts thus far referred to and briefly

described are well known, being plainly disclosed in my aforesaid patent, and consequently they do not require a more detailed description here; such parts form no part of my present invention except in the novel 76 combinations hereinafter pointed out in the claims.

Oil is supplied between the two tubes 6 and 7 by the pipe sections 18 and 19, through a pipe or flexible hose 23 and a strainer 24 75 (Figs. 1 and 2). The hose 23 is connected with a pipe 25 leading to a T-section 26 to which is connected a casing 27 having at its lower end a sediment trap 28 which may be cleaned out by a valve. A tube 29 has a 80 flanged end, and extends through and is spaced from the inner walls of pipe 26 casing 27. The upper end of the strainer is secured to the outer wall of tube 29, and the lower end of the strainer is secured to 85 the lower part of the inner wall of the casing 27. The branch 30 of the T-section is secured to the branch of a four-way joint 31, the upper branch *b* of which is secured to or integral with the pipe section 17. Said joint contains a right angle valve 32, which, as shown in Figure 2 is set to connect branches *a* and *b* for supplying the burner with fuel. When it is desired to stop firing, the valve 32 may be set to connect branches 90 *b* and *c*, which will cut off the supply of oil to the burner and permit the oil in the burner, above the valve, to drain back into hose 33 leading to any appropriate receptacle. When it is desired to clean out the 95 supply tank from which the hose 23 extends, the valve 32 is set to connect branches *a* and *d*.

Figures 1 and 2, as well as Figures 4 and 5, disclose an air valve for controlling the 105 flow of air between the outer surface of the ring 14 and the inner wall of the nozzle 3 (or of the ring 53 of Fig. 5). In the present specification and in the claims, the word "nozzle", when used in connection with the 110 ring 14 and the valve now about to be described, is to be taken as including, when the context demands or permits, the ring 53, which is in effect a part of the nozzle when the smaller ring 14 is used. The valve comprises two semi-circular plates 70, riveted or otherwise secured to buttons 71 whose shanks fit closely in openings in the nozzle 3 and are notched at 72 to be held in the desired, 115 adjusted position of extension or retraction by spring blades 73 secured to the outer wall of the nozzle. Figures 1 and 3 show the upper valve plate 70 positioned to close the air passage which it controls, and the lower valve plate retracted to open its passage. With this adjustment the flame will be directed upwardly more or less, and the opposite will be true if the positions of the valve plates be reversed. When both plates 120 are set to close their passages, the flame will 125 130

be less intense, due to reduction in the air supply. It will be noted that the nozzle 3 has an annular internal groove to receive the valve plates 70 when they are retracted. 5 This groove is unnecessary when using the ring 53 of Figure 5.

In Figure 1, a pipe or flexible hose 75 connects the elbow section 1 with the nipple 43 of joint 42 to supply air from the conduit 5 10 to the rear end of the inner tube 7. Such air supply may be controlled by a valve 76.

Again referring to Figure 1, I have provided improved means for cleaning out the oil passageway 4 between the nested tubes 15 6 and 7 when firing has been stopped. A pipe section 77 is screwed into the joint 20 and receives a valve 78. Above this valve the sleeve 2 has a threaded opening receiving a short pipe section 79 over which is screwed 20 a handle 80. The upper part of the valve 78 is extended through the section 79 and is guided thereby in its rotation. The top 81 of the valve is reduced and squared and is non-rotatably secured in the squared stem 82 25 of handle 80. A passage 83 is formed through the upper part of the valve and is closed by a screw 84. The valve is held firmly on its seat by a spring 85 compressed between the screw 84 and the handle 80. If desired, the base of the handle may have a semi-circumferential groove cooperating with a spring-pressed pin 87, to limit the turning of the handle to the arc necessary 30 for opening and closing the valve.

Ordinarily in clearing out the tubes 6 and 7 after the valve 32 has been closed, the valve plates 70 are positioned to close the passage between the nozzle and the ring 14, the plate 10 is retracted (or, in Fig. 5 projected) until it substantially closes the passage between it and ring 14, and the valve 78 is turned 180° to admit air from the elbow joint 1 to the pipe section 77 and the nested tubes. Air is also supplied to the inner tube through the 45 pipe or hose 75. If steam is available, the handle 80 may be readily removed from the pipe section 79, and a steam connection may be attached to the valve 78 after removal of the screw 84.

The burner as a whole may be rotated about the air conduit 5 as an axis. Said conduit has its upper end screw threaded to receive a collar 89 locked in place by set screws 90. The elbow 1 is rotatably mounted on 50 said collar and held in any desired position of adjustment by set screws 91. In Fig. 1, the short forward part of the valve stem 8 (the part within the base of plate 10) is flattened at 92 to triangular form, and fits, but is slidable axially within, the inner tube, so as to prevent wobbling. Another formation is shown in Fig. 4, where the enlarged forward part of the valve stem is helically grooved, and fits and slides as has been explained above. The disclosure in Fig. 5 is

similar to that of Fig. 4 in my said Patent No. 1,588,634 in that there is no valve. However, in Fig. 5, a sheet metal strip 94 is twisted to helical form and held in place by friction in the inner tube 7. This latter arrangement, as compared with the two first described, produces the longest flame, and is not used for producing a spherical broad flame.

I claim as my invention:

1. A burner comprising a casing, nested tubes within the casing and affording fuel passageways and providing atomizing means at their outlet ends, a plate supported by and surrounding the atomizing means, a co-operating ring having a conical inner surface surrounding the plate, means for axially adjusting at least one of the tubes with respect to the ring, a nozzle surrounding and supporting the ring with clearance between said nozzle and said ring, and a valve mechanism in proximity to the ring and comprising means adapted to control independently the flow of air through different arcuate portions of the clearance between the ring and the nozzle.

2. A burner according to claim 1, in which the valve comprises arcuate, plate-like valve elements each having a handle secured thereto for projecting each valve plate into position to obstruct the air passage between the nozzle and the ring, and for withdrawing the plate from such position.

3. In the burner as claimed in claim 1, an air conveying conduit between the casing of the burner and the rear end of the nested tubes.

4. A burner comprising nested tubes affording fuel passageways and providing atomizing means at their outlet ends, a valve for the inner tube and a valve stem for said valve extending through said inner tube, said stem being substantially polygonal in cross section throughout a portion of its length at its forward end, the edges of such polygonal formation slidably engaging the inner wall of the inner tube, a deflector plate supported by and surrounding the atomizing means, a co-operating ring having a conical inner surface surrounding the deflector plate, means for adjusting at least one of the tubes with respect to said ring, and a nozzle surrounding and supporting the ring, which is reversibly mounted in said nozzle and has an axial length substantially equal to the maximum distance through which the tubes are adjustable, the minor inside diameter of said ring being substantially equal to the diameter of said deflector plate.

5. A burner comprising a nozzle, nested tubes adjustable lengthwise therein and having atomizing means at their outlet ends, means for supplying fuel through the nozzle and to the tubes at a point intermediate their ends, said fuel-supplying means serv-

ing to support the tubes, and including a four-way fitting which is disposed outside the nozzle and supported thereby, said fitting containing a valve, and having its first passage connected with a fuel supply pipe, a sediment trap and a strainer, its second passage connected with the tubes and the nozzle, its third passage connected with a drain-off pipe, and its fourth passage connected with said drain-off pipe through a ¹⁰ by-pass.

In testimony whereof I affix my signature.

LUDWIG WALLSTROM.
